DESIGN FOR A COMBINED DISPLAY AND RETAINER SUPPORT

Guy E. Noel, Muncie, Ind.

Application May 17, 1937, Serial No. 69,391

Term of patent 7 years

To all whom it may concern:

Be it known that I, Guy E. Noel, a citizen of the United States and a resident of Muncie, county of Delaware, and State of Indiana, have invented a new, original, and ornamental Design for a Combined Display and Retainer Support, of which the following is a specification, reference being had to the accompanying drawing, forming part thereof.

In the drawing, the figure is a perspective view of the combined display and retainer support, showing my new design.

I claim:

The ornamental design for a combined display and retainer support as shown.

GUY E. NOEL.
